UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

OIL-DISPENSING DEVICE.

Application filed January 18, 1923. Serial No. 612,540.

To all whom it may concern:

Be it known that I, CHARLES SPAETH, a citizen of the United States, residing at Cleveland, in the county of Cuyahoga and State of Ohio, have invented certain new and useful Improvements in an Oil-Dispensing Device, of which the following is a specification.

The present invention comprises an apparatus especially constructed to dispense oil or other liquids with convenience and despatch and without loss and waste, and the apparatus is also designed to prevent theft and unauthorized withdrawal of oil from a supply tank or receptacle having a cover or lid at its top adapted to be conveniently opened to permit the tank to be filled and its contents inspected. The oil is delivered into a measure or vessel adapted to be held in the hand and a free and uninterrupted return flow of the drip or surplus oil to the tank is automatically provided for when the receiving vessel is withdrawn from beneath the delivery spout. The return passage to the tank is perpendicular and straight or without bends or elbows to promote drainage into the tank without restraint and overflow, either under drip or mere gravity discharge from the delivery spout, or under a forced discharge of the oil in full volume if pumping operations are willfully or inadvertently continued. For other and more specific objects and details reference may be had to the following description and annexed drawings. Thus in the drawings Fig. 1 is a front elevation of a complete dispensing apparatus constructed according to my invention, with a receiving vessel in place beneath the delivery spout. Fig. 2 is a front view of the apparatus, showing the tank cover tilted into an open position. Fig. 3 is an enlarged vertical section of the upper end of a tank and its parts on line 3—3 of Fig. 4, the drain pipe being shown locked in a perpendicular draining position. Fig. 4 is a side view of the pump and drain and a sectional view of the cover and tank.

In garages and other places where oil is being constantly handled and dispensed, it is customary to provide either stationary or portable supply tanks 2 equipped with delivery spouts or faucets 3 which are usually connected with a pump 4 adapted to withdraw a measured or predetermined

amount of oil from the tank. In the present instance I mount the pump 4, which may be of any suitable kind or style, upon the top 5 of the tank, and provide a lateral discharge pipe 6 at the upper end of a transparent or glass discharge column 7 affixed to the pump. A gooseneck delivery spout 8 is detachably secured to pipe 6 by a union nut 9, although this spout may be an integral part of the pipe or column, if desired. The mouth of spout 8 is preferably enlarged and formed with a depending flange 10 on three sides to provide a water-shedding hood or cap which is open at one side. A lateral flange 11 above this open side provides a further weather-guard at this point, and this flange may be perforated to permit a padlock 12 to be detachably connected therewith opposite the opening in the side of the cap. Directly beneath the mouth of the spout and axially in line therewith is a pendulum drain pipe 14 extending upwardly from the center of a hinged cover 15 for a filling opening 16 in top 5. This filling opening is also directly beneath the mouth of the spout, and when the drain pipe is locked within the mouth of the spout by padlock 12 or an equivalent locking device, it is obvious that neither the cover 15 nor the drain pipe 14 can be tilted or removed. The hasp of the padlock projects beneath the lateral flange 11 and bars outward movement of the enlarged end of drain pipe 14, but removal of this padlock permits the drain pipe to be tilted to an angle of substantially forty-five degrees as shown in Fig. 1, and such tilting is easily effected by mere contact of the receiving vessel R with the drain pipe. The limit of movement of the drain pipe may exceed that shown, but in the present instance the pipe is stopped at that angle by striking the inclined portion 18 at one end of the slot 19 in cover plate 15, and a square shoulder 20 at the opposite end of slot 19 provides a stop when the drain pipe assumes a perpendicular position under the control of a ball or counterweight 21 which is sleeved and fastened upon the lower end of the drain pipe within tank 2.

To permit the drain pipe to assume the desired angle of inclination the counterweight 21 is suspended at some distance beneath and apart from the cover plate, therefore, when tank 2 is full of oil the

counter-weight is submerged, but a series of lateral outlets 22 within drain pipe 14 relatively near cover plate 15 permit the oil to escape freely and prevent backing up 5 and overflow of the oil at the delivery spout when a sudden rush of oil occurs or if the oil is thick or sluggish in movement as in heavy oils or in cold weather. For the same reason drain pipe 14 is made straight and 10 counterweighted to stand perpendicularly in line with the discharge spout to prevent any check in the flow of the oil after it leaves the spout. Thus, if the operator continues pumping operations inadvertently, or 15 when unauthorized persons seek to withdraw oil from the tank while the drain pipe is upright, the flow of oil through the drain pipe will not be impeded or obstructed by bends or elbows and the oil will circulate 20 freely and not overflow at the upper end of the drain pipe. The drain pipe may also be made of larger diameter than the discharge opening in the spout to promote rapid drainage under pumping operations. 25 To permit the drain pipe to tilt and also to be bodily raised within limits in respect to cover plate 15, a semi-circular recess or socket 23 is formed within the upper side of plate 15 wherein a cylindrical bearing 30 or trunnion member 24 on pipe 14 is adapted to rest and rotate. Member 24 is sleeved upon pipe 14 and adjustably fastened thereto by a set screw 25 which is covered and made inaccessible by the straight side or wall 26 35 of the recess or socket when said bearing member is seated, and socket wall 26 is also covered and concealed by a closely-fitting hood 27 fixed upon the drain pipe by a set screw 28. The upper end of the socket or 40 recess is otherwise open so that the bearing member may be lifted bodily therefrom, providing the drain pipe is not in a perpendicular position and locked within the mouth of the spout. This uplift of the 45 drain pipe is only effected when the hinged cover 15 is to be thrown back as shown in Fig. 2, and when the counter-weight must be raised sufficiently to clear the edge of the filling opening in its arc movement upwardly out of the tank. Thus Fig. 2, shows the shifted separated position of the drain pipe and its fixed parts relatively to the socket within the hinged cover plate. The 50 opposite end walls 29—29 of the socket have 55 adjusting screws 30—30 which permit the cylindrical bearing member 24 to be shifted within limits longitudinally of its axis upon the raised seats 31 within socket 23, thereby permitting the drain pipe to be placed 60 axially in line with the center of the mouth of the spout without shortening or extending the length of spout or changing the fixed setting of the pump on the tank. Hood 27 on pipe 14 covers and protects the socket 65 and bearing member, and one wall 33 of the

socket is curved to permit this hood to turn downwardly toward the cover plate in tilting the drain pipe. Cover plate 15 is seated upon a sealing ring 34 which is fastened to the top 5 of tank 2 by screws 35 or in any other suitable way, and perforated projections 36 may be formed at one side or on opposite sides of this ring and plate to provide a hinge connection 37. Where two sets of such lugs are provided on opposite sides 75 as shown in Fig. 2, one set may be used for a hinge connection and the other set for locking purposes, using a padlock or other locking member. However by employing a single lock at the spout the drain pipe 14 80 may be locked against sliding and tilting movement and the cover 15 also prevented from being opened or removed. Instead of using a padlock I may employ instead a snap lock or other self-locking device requiring a key to unlock the same before permitting the drain pipe to be shifted. Thus, after each withdrawal of a measured amount of liquid the drain pipe would return and lock automatically beneath the mouth of the 85 spout. 90

What I claim is:

1. An oil dispensing apparatus, comprising a receptacle having a delivery spout, and an oscillatory drain pipe having a horizontal axis intersecting a straight line from the mouth of said spout to the interior of said receptacle. 95

2. An oil dispensing apparatus, comprising a receptacle having a delivery spout, a straight drain pipe for said spout pivotally connected with said receptacle, and a counterweight adapted to swing and maintain said pipe automatically in a perpendicular position axially in line with the 100 mouth of said spout. 105

3. An oil dispensing apparatus, comprising a storage receptacle having a dispensing device provided with a spout extending above the top of said receptacle and a drain pipe mounted upon a horizontal axis in a perpendicular oscillatory position upon said receptacle in axial alignment with the mouth of said spout and communicating at its lower end with the interior of said receptacle. 110 115

4. An oil dispensing apparatus, comprising a storage tank having a pumping device and a delivery spout and provided with a drain pipe extending on a straight line from the mouth of said spout into the upper end of said tank, said drain pipe being rotatably mounted on a horizontal axis and provided with a counterweight within said tank. 120

5. An oil dispensing apparatus, comprising a storage tank having a dispensing pump provided with a delivery spout extending above the top of said tank, and a straight drain pipe mounted perpendicularly upon a rocking support above the top of 125 130

said tank in line with the mouth of said spout, said pipe extending into said tank and having a counterweight sleeved thereon.

6. An oil dispensing apparatus, comprising a storage tank having a pumping device and dispensing spout, and a cover for said tank having a drain pipe mounted to rock thereon on a horizontal axis into a perpendicular draining position beneath the mouth 10 of said spout, said pipe communicating at its lower end with the interior of said tank.

7. An oil dispensing apparatus, comprising a tank having a pump-operated dispensing device connected therewith, and a 15 removable cover for said tank having a counter-balanced drain pipe mounted to oscillate thereon on a horizontal axis and extending upwardly into drainage relation with said dispensing device.

20 8. An oil dispensing apparatus, comprising a storage receptacle having a pump provided with a discharge spout extending above the top of said receptacle, said tank having a filling opening in its top beneath 25 said spout, a removable cover plate for said opening having a bearing recess therein, and an oscillatory drain pipe having a bearing member seated in said recess.

9. An oil dispensing apparatus, comprising 30 a storage receptacle, a dispensing pump connected with said receptacle having a discharge spout extending above the top of said receptacle, said top having an opening therein beneath said spout, a removable 35 cover for said opening, a drain pipe extending through said cover and mounted in an oscillatory position thereon perpendicularly in line with said spout, and a counterweight affixed to the depending end of 40 said pipe within said receptacle.

10. An oil dispensing apparatus, comprising 45 a storage receptacle having a hinged cover at its top, a dispensing pump for said receptacle having a delivery spout extending above said top opposite said cover, and a drain pipe mounted on a horizontal axis in an oscillatory position upon said cover in line with the mouth of said spout and having 50 open communication through said cover with the interior of said receptacle.

11. An oil dispensing apparatus, comprising 55 a storage receptacle having a cover plate at its top, a dispensing device connected with said receptacle having a delivery spout extending above said cover plate, and a drain pipe for said delivery spout having a horizontal axis in loose detachable oscil-

latory connection with said cover plate and open at its lower end to the interior of said receptacle.

60 12. An oil dispensing apparatus, comprising a storage receptacle having a dispensing pump and spout connected therewith, and an oscillatory drain pipe for said spout extending into the upper end of said receptacle having a counterweight thereon and provided with lateral escape openings for the oil above said counterweight.

65 13. An oil dispensing apparatus, comprising a storage receptacle, a dispensing pump connected with said receptacle having a delivery spout, a counter-balanced drain pipe supported to oscillate beneath said spout and extending into the upper end of said receptacle, said pipe being open at both 70 ends and provided with lateral outlets intermediate said ends within the upper end of said receptacle.

75 14. An oil dispensing apparatus, comprising a storage receptacle having a dispensing pump connected therewith and a delivery spout extending horizontally above said top from said pump, an oscillatory drain pipe having a rocking support at the top of said receptacle and movable to a perpendicular position in line with the mouth of said spout, and adjustable devices associated 80 with said rocking support adapted to permit axial alignment between said drain pipe and the mouth of said spout.

85 15. An oil dispensing apparatus, comprising a storage receptacle having a dispensing spout extending horizontally above its top, a drain pipe having a cylindrical bearing member sleeved thereon, a supporting member at the top of said receptacle provided with an open socket for said bearing member, and a cap member fixed to said pipe in covering relation to said socket and bearing member.

90 16. An oil dispensing apparatus, comprising a storage receptacle having a dispensing spout, a cover plate for said receptacle having an open socket at its upper side and a slot at its bottom side open to said socket, a drain pipe opposite said spout extending through said slot and socket having a trunnion member seated within said socket, and means on said pipe covering said socket and trunnion member.

100 In testimony whereof I affix my signature hereto.

CHARLES SPAETH.
